D. S. COOK & J. P. FINK.
ADJUSTABLE GAS ENGINE MUFFLER ATTACHMENT.
APPLICATION FILED JUNE 3, 1918.

1,287,239.

Patented Dec. 10, 1918.

UNITED STATES PATENT OFFICE.

DON S. COOK AND JOSEPH P. FINK, OF NORTH EATON, OHIO.

ADJUSTABLE GAS-ENGINE-MUFFLER ATTACHMENT.

1,287,239.

Specification of Letters Patent. Patented Dec. 10, 1918.

Application filed June 3, 1918. Serial No. 237,960.

To all whom it may concern:

Be it known that we, DON S. COOK and JOSEPH P. FINK, citizens of the United States, residing at North Eaton, in the county of Lorain and State of Ohio, have invented certain new and useful Improvements in Adjustable Gas-Engine-Muffler Attachments, of which the following is a specification.

10 Our invention relates to improvements in an adjustable attachment for gas engine mufflers, and is herein explained in connection with a type of muffler especially designed for use upon automobiles. The object of our invention is to effect a saving of fuel, avoid the collection of carbon or soot in the muffler, permit the easy starting of the engine, and the attainment of other advantages inherent in the use of apparatus within the scope of our said invention.

15 We have applied to the muffler, which may be of any approved type, an appliance which is adapted to permit the operation of the muffler in its usual manner, or 20 through the adjustment of said appliance, permit the exhaust from the gas engine to pass more directly through the muffler and thereby avoid a tendency to deposit carbon within the walls of the muffler, and further 25 avoid material back pressure therein.

30 Our invention may be more readily explained in connection with the accompanying drawings, wherein:

Figure 1 is a view partially diagrammatic and in section, illustrating a muffler equipped with our attachment and the use thereof.

Fig. 2 is an end view, and Fig. 4 a vertical sectional view of our attachment, with the 35 vanes or valve mechanism closed,

And Figs. 3 and 5 are corresponding views showing the vanes in their fully open position.

Throughout the several figures of the 40 drawings, the same character of reference has been applied to indicate similar parts of the mechanism shown.

Referring first to Fig. 1, a muffler is somewhat diagrammatically shown in connection 45 with our appliance and operating means therefor, wherein the exhaust pipe *a* from

the engine enters the cylindrical muffler chamber *b*, surrounded by casing *c*, and the exhaust finds exit from the pipe *d*. The muffler chamber is provided with a plurality of perforations arranged in sets *b'* and *b''*, while our attachment is interposed approximately two-thirds of the length of the muffler chamber at *e*, between said sets of perforations. A bell-crank lever *f* is provided for the actuation of said attachment, through the medium of a controlling lever *g* and the connecting link *h*, as indicated in Fig. 1.

The mechanism for operating the vanes in said attachment is best shown in the remaining figures of the drawings. The extension *f'* of the bell-crank lever is pivoted diametrically of the cylindrical shell *i*. The central vane *j* is secured to said extension by means of nuts and screws *i'*. The upper and lower vanes *k* and *l*, completing the circular valve mechanism or obstruction within said shell, respectively are mounted upon the short shafts *k'* and *l'* and these are connected for actuation to the median vane *j* by means of the U-shaped links *k''* and *l''*, respectively pivoted thereto as shown. These links afford one means for connecting said vanes so that they may be concurrently actuated to close or obstruct the muffler chamber, or practically clear said chamber of obstruction, or adjust such obstruction in any desired degree; all depending upon the angular positions of these vanes. These sectional vanes or shutter members are subjected to intense heat which would warp out of shape those of larger dimensions, unless formed of very heavy material. Also, said members are stiffened by being mounted on separate supporting shafts.

When our attachment has been applied to a muffler, it will be found practicable to operate the gas engine quite commonly, with the vanes in their fully open position. With said vanes partially closed, the action of the muffler naturally is increased, although with little accompanying increase in the back pressure of the exhaust line from the engine. An automobile may be operated satisfactorily under both conditions; the

- escape of the exhaust through the openings in the muffler chamber as indicated by the arrows, varying with the adjustment of the vanes, yet securing a quiet operation of the engine. This appears to result from a whirling action set up in the spent gases, which find exit partly through the perforations, even with the vanes in their wide open position, thus smothering the exhaust.
- 10 Of course, the maximum effect of the muffler is obtained by completely closing the vanes, as shown in Figs. 2 and 4, but intermediate adjustments of said vanes or valve mechanism, to suit the running conditions and desires of the driver, ordinarily are preferable and permissible.

The use of our attachment with any suitable type of muffler, will demonstrate that more or less saving of gasolene is thereby effected in operating the engine, while said engine obviously may be started more readily with the vanes wide open, than with the ordinary muffler. It will be found also, that there is little accumulation of soot or carbon in the muffler. Moreover, the attachment is simple, is not liable to get out of order, and it is instantly adjustable from the driver's seat of an automobile, or from any desired position with respect to a stationary gas engine.

Having now described the preferred embodiment of our invention, and one of its practical applications, we claim as new, and desire to secure by Letters Patent, the following:—

1. In apparatus of the class described, the combination with a gas engine muffler, of an attachment therefor comprising three coacting shutter members together forming a complete valve mechanism for the muffler chamber adapted entirely to close the same, three independent shafts respectively mounting and reinforcing the sectional shutter members, and means for concurrently operating said valve members, substantially as set forth.

2. The combination with a muffler comprising terminally vented connecting outer and inner chambers, of an adjustable closure mechanism mounted in the latter, comprising a cylindrical shell, three parallel shafts positioned therein substantially in a common plane, three sectional vanes respectively secured thereto and together adapted to be actuated into substantially the plane of said shafts completely to obstruct the inner chamber; one of said shafts being extended exteriorly of the device, means removably connecting it to the corresponding sectional vane, and additional means for concurrently operating the vanes thereby, substantially as set forth.

3. In apparatus of the class described, the combination with a gas engine muffler, com-

prising an outer casing and an inner muffler chamber having perforated walls adjacent to its ends, and an insertible and removable attachment positioned within said muffler chamber comprising a containing casing and valve mechanism adapted to obstruct said chamber, with means for actuating said valve mechanism from a distance, substantially as set forth.

4. In apparatus of the class described, the combination with a gas engine muffler, comprising outer and inner communicating muffler chambers; the latter being perforated adjacent to its ends, of an adjustable closure therefor comprising a plurality of sectional shutters or vanes together adapted to form a complete obstruction for the intermediate portion of the inner chamber, independent shafts respectively mounting said shutters intermediately thereof for staying them against warping, and connecting means for securing their common actuation substantially into a given plane or alternatively into parallel relation, for closing or opening said intermediate portion of the inner chamber; said adjustable closure being removably mounted as a unit within the muffler, substantially as set forth.

5. In apparatus of the class described, an attachment for gas engine mufflers, comprising a cylindrical casing, three rotatable shafts mounted in parallel relation therein, three vanes respectively mounted upon said shafts, and together forming a complete obstruction when adjusted for deflecting the exhaust, interior links uniting said vanes for concurrent movement, and means for actuating the same, substantially as set forth.

6. In an adjustable attachment for gas engine mufflers, the combination with a supporting shell, of a plurality of shutters mounted therein normally to clear the passage therethrough, but adapted substantially to close the same upon variable adjustment thereof; said shutters together forming a complete closure when adjusted for deflecting the exhaust, and means for actuating the said shutters, substantially as set forth.

7. In apparatus of the described type, the combination with a muffler having an inner chamber and exterior passages communicating therewith, of an insertible and removable attachment positioned intermediately of said inner chamber and the communicating passages, comprising sectional, stiffened or stayed adjustable members adapted substantially to close said chamber but permitting free passage therethrough when desired, and means for actuating said members into any desired positions of adjustment from the outside of said muffler, substantially as set forth.

8. In an adjustable attachment for gas engine mufflers, the combination with a sup-

porting shell, of a plurality of sectional shutters together forming a complete obstruction when properly adjusted within the shell, independent shafts for each shutter, interior connecting means, and an actuating shaft removably connected for operating said shutters, substantially as set forth.

In testimony whereof we do now affix our signatures in the presence of two witnesses.

DON S. COOK.

JOSEPH P. FINK.
